UNITED STATES PATENT OFFICE.

FREDERICK WILLIAM TOEDT, OF HAMBURG, IOWA.

GAS-ENGINE.

SPECIFICATION forming part of Letters Patent No. 651,216, dated June 5, 1900.

Application filed August 5, 1899. Serial No. 726,271. (No model.)

To all whom it may concern:

Be it known that I, FREDERICK WILLIAM TOEDT, of Hamburg, in the county of Fremont and State of Iowa, have invented a new and Improved Gas-Engine, of which the following is a full, clear, and exact description.

My invention relates to improvements in gas-engines, and comprises the novel features hereinafter described and claimed.

Reference is to be had to the accompanying drawings, forming a part of this specification, in which similar characters of reference indicate corresponding parts in all the figures.

Figure 1 is a sectional elevation of my device, taken through the power and the pump cylinders. Fig. 2 is a cross-section taken through said cylinders. Fig. 3 is a section taken through the pump-cylinder and showing one edge of the power-cylinder and the means for exploding the gaseous mixture, and Fig. 4 is a section through the valves controlling the admission and discharge of the gaseous mixture to and from the pump.

The engine herein shown is a vertical engine; but it is evident that the construction of the cylinder and pistons may be applied to horizontal engines as well.

The power-cylinder A is provided with an outer casing A', forming a cooling-jacket *a* between the two. This jacket is supplied with fresh air which is pumped by means of a piston N', which is connected, by means of a rod N², directly with one section D' of the power-piston. The cylinder N, which contains the piston N', is provided with the usual inlet-valves *n*, located at each end thereof, and the discharge-valves *n'*, said valves being of any ordinary or usual form, such as the usual check-valves. The air-cylinder N is connected with the air-jacket by means of a pipe *n*². By this means a constant circulation of cool air about the engine-cylinder is provided for, which will keep the same at a reasonable temperature.

The power-piston is divided into two sections D and D', which are connected with each other by means of a stem D². The section D, being the section farthest removed from the crank, is the one which is acted upon by the pressure within the cylinder, while the section D' acts mainly as a valve or plug to close the outer or open end of the cyl-

inder A. The section D' also acts as the cross-head, having a pin journal edtherein to which the connecting-rod H is attached. The 55 connecting-rod H at its other end is journaled upon a pin upon the cranks I', which are secured to the main shaft I after the usual manner.

The gaseous mixture is supplied to the power explosion-chamber by means of a pump which is located alongside of the power-cylinder and is contained within a cylinder composed of two parts B and B', the inner cylinder B' being slideable lengthwise of the 65 outer cylinder. The pump-piston P, which slides within the inner cylinder B', is connected by means of its rod P' with an arm P², said arm being connected with a rod P³, which at its other end is fixedly secured to 70 the outer section D' of the power-piston. The pump-piston therefore moves in exact accord with the power-piston.

The gaseous mixture is supplied to the pump-cylinder through a passage B² and passage B³ and a check-valve T, which is connected with the passage B³. These parts are clearly shown in Fig. 4. The air is supplied to the valve T through a pipe T', which connects with a chamber T², within one wall of 80 which the valve T is placed. The gas is supplied to this chamber through a pipe T³, which is connected with one side thereof. The passage B³ connects with the outer cylinder B. The cylinder B' is provided at its inner end 85 with a series of longitudinally-extending bypass ports b², which are of such a length that the outer ends thereof will be just uncovered by the piston P when the same is at the inner point of its stroke and when the inner cylinder B' is at its inner position relative to the outer cylinder B. This position is the one which is shown in Fig. 1.

The inner cylinder B' is provided with a flange *b* at its inner end, by which the cylinder is centered and supported within the outer cylinder B. It is also provided with a similar flange b', located near the center thereof, but at such a distance from the inner end that it will never reach the by-pass 95 ports b². The outer portion of the inner cylinder B' is provided with a rack L', which is adapted to be engaged by a worm L, mounted upon a shaft K², which is journaled in one

end of the cylinder B or in any other fixed support. It is evident that if the shaft K² and worm L be rotated the inner cylinder B' will be moved inward or outward, depending 5 upon the direction of rotation of such worm. This worm may be turned by hand, if desired, or be connected with any suitable governor, so as to control the position of the inner pump-cylinder automatically by said governor. A connection of this sort is shown in 10 Fig. 1, consisting of a bevel-pinion K', secured upon one end of the shaft K² and adapted to alternately mesh with one of a pair of bevel-gears k' and k², mounted upon a sleeve 15 which is slideable upon but turns with the engine-shaft I. This cylinder is controlled in position by the governor K, which may be of any suitable construction. When the governor is in its central position, the pinion K' 20 will not be engaged by either of the gears k' and k².

If the speed should fall below that desired, the sleeve will be moved in such a direction as to move the cylinder B' inward and postpone 25 the point where the by-pass ports will be engaged by the piston P, while if the speed should be above that desired the sleeve will be moved in the opposite direction and cause the by-pass ports to be uncovered at an earlier 30 point in the stroke of the pump-piston P, thus decreasing the amount of the gaseous mixture which is forced into the power explosion-chamber.

An auxiliary head M is mounted to slide 35 upon the rod P' of the pump-piston. This head is provided with suitable packing-heads, by which a tight joint is maintained between the same and the piston-rod and also between the auxiliary head and the cylinder B'. This 40 head is normally held toward the piston-head P by means of a spirally-coiled spring M', which surrounds the piston-rod P' and which is supported at its outer end by a collar p, secured to said piston-rod.

45 In the operation of the pump when the piston-head P uncovers the outer ends of the by-pass ports b² the gaseous mixture which has been compressed in front of the piston is allowed to escape to the outer side thereof, 50 thus acting upon the auxiliary head M and causing the same to stop in its advance. The uncovering of the by-pass ports by the piston P permits the valve R', which controls the admission of the gaseous mixture to the 55 power-cylinder, to close, so that no more of the gaseous mixture will be forced into said power-cylinder. The pressure within the power-cylinder is thus controlled by the amount of the gaseous mixture which is introduced 60 at each stroke. The surplus gas which is contained within the pump-cylinder is allowed to escape to the rear side of its piston and is held against discharge into the outer air by means of the sliding auxiliary head M. When the pump-piston P returns, the gas which is contained between said piston and the auxiliary head M passes back to

the opposite side of the piston P, and the auxiliary head M does not start in its return motion until the piston P has completely covered the by-pass ports b².

The passage B³, through which the gaseous mixture is conducted to the explosion-chamber or the power-cylinder, does not connect directly with the power-cylinder, but with 75 one end of the explosion-chamber R, as is clearly shown in Fig. 3. This explosion-chamber consists of a long and relatively-small passage, which at one end connects with the passage B³, leading to the pump-cylinder, and at its other end connects with the power-cylinder. The exploding device is located in this explosion-chamber farthest removed from the power-cylinder, as is shown in Fig. 3. Any form of explosion device desired may be used for this purpose. I have herein shown an electric igniter or exploding device which consists of an insulated pin S', which is connected with one side of the battery, and an arm S, which is mounted upon 90 a shaft S², which extends through one wall of the explosion-chamber and at its outer end is provided with an arm S³, adapted to be engaged by an arm S⁴, carried by the outer end of the rod P³, which is connected with the 95 power-piston and which operates the pump-piston.

The action of the attenuated explosion-chamber R is to prolong the period of explosion, as the ignition of the gases has to travel 100 from one end of the explosion-chamber to the other, which will consume some little time, due to its length and the small cross-section. As a result of this the pressure developed at the beginning of the stroke of the power-piston is less than where the ignition of the gaseous mixture is complete and immediate, the terminal pressure also being raised from the same cause. The explosion-chamber R is 105 preferably cast-within the walls of the cylinder A, as shown in Fig. 2. The pump-cylinder 110 B is also preferably formed in the same manner as a part of the main casting or that which contains the main cylinder A.

The portion D of the power-piston is provided with exhaust-ports G, which pass through the body thereof and which are arranged in a circle surrounding its center. These ports G are adapted to be closed by a valve E', which is placed upon one end of a 120 stem E, said stem extending within a hole formed within the center of the piston D and the stem D², which connects said piston with the other section D' thereof. Beneath the inner end of the stem E is placed a spirally-coiled spring e, the normal tendency of 125 which is to keep the valve E' raised from the ports G. The valve E' and the stem E have a central bore or hole which contains a pin F and a spring F', which acts upon said pin 130 to project it where it will be engaged by the end of the cylinder when the piston nears the upper end of its travel. When this pin strikes the cylinder-head, it will compress

the spring F', and thus exert a pressure upon the stem of the valve E', which will tend to seat it and cause it to close the ports G. This will result in seating the valve E' just prior to the termination of the return stroke of the piston D. The ports G will thus be closed at the time when the charge within the explosion-chamber is ignited and pressure is applied to the piston D. This pressure acting upon the valve E' will be sufficient to keep it seated and the ports G thus closed.

The exhaust-ports for the cylinder A are located in the cylinder at such a point that they will be uncovered by the piston D at the termination of the power-stroke thereof. The pressure within the cylinder will thus be discharged through the exhaust-pipe Q'. As a consequence of the reduction of pressure within the cylinder the spring e will be enabled to lift the valve E' from its seat, thus opening the ports G and permitting the spent products, which are still trapped within the cylinder after it has moved on its return stroke an amount sufficient to cover the ports Q, to escape through the ports G and Q, said ports Q being open until they are closed by the outer section D' of the piston. When these ports are thus covered, the ports G have been closed by the action of the pin F striking against the outer end of the cylinder A.

Having thus fully described my invention, I claim as new and desire to secure by Letters Patent—

1. A pump for delivering the gaseous mixture to gas-engines, comprising a cylinder having by-pass ports controlled by its piston, a piston reciprocating therein, and means for confining to the cylinder the gas escaping through said ports, as set forth.

2. A pump for delivering the gaseous mixture to gas-engines, comprising a cylinder having by-pass ports controlled by its piston, a piston reciprocating therein, means for moving the cylinder relative to the piston-stroke, and means for confining to the cylinder behind said piston the gas escaping through said by-pass ports, as set forth.

3. A gas-engine, comprising a power cylinder and piston, means for exploding the gaseous mixture, a pump cylinder and piston for injecting the gaseous mixture, the pump-cylinder having ports therein forming a by-pass adapted to communicate with opposite sides of its piston, and means for shifting the location of the cylinder relative to the stroke of the piston to vary the time of opening of the by-pass, substantially as described.

4. A gas-engine, comprising a power cylinder and piston, and means for exploding a gaseous mixture, in combination with a pump for the introduction of the gaseous mixture, said pump comprising a fixed cylinder, a pump-cylinder slidable therein, the pump-cylinder having ports or by-passes therein adapted to communicate with opposite sides of the pump-piston, a pump-piston within the slidable cylinder, and means for sliding the

inner cylinder to vary the time of opening of the by-pass, substantially as described.

5. A pump for delivering the gaseous mixture to gas-engines, comprising a cylinder having by-pass ports controlled by its piston, a piston reciprocating therein, and means for moving the pump-cylinder relative to the piston-stroke whereby the time of opening of the by-pass is varied, substantially as described.

6. A pump for delivering the gaseous mixture to gas-engines, comprising a cylinder having by-pass ports controlled by its piston, a piston reciprocating therein, a governor, and means controlled by the governor for giving the cylinder movement relative to the piston-stroke whereby the time of opening of the by-pass is varied, substantially as described.

7. A gas-engine, comprising a power-cylinder and piston therein, a pump-cylinder comprising two cylinders one within the other, the inner cylinder having ports or by-passes adapted to connect with opposite sides of the pump-piston and the outer cylinder being connected with the power-cylinder, and means for reciprocating the inner cylinder to vary the time of opening of the by-pass, substantially as described.

8. A gas-engine, comprising a power-cylinder and piston therein, a pump-cylinder comprising two cylinders one within the other, the inner cylinder having ports or by-passes adapted to connect with opposite sides of the pump-piston and the outer cylinder being connected with the power-cylinder, a rack secured to the inner cylinder, a governor, and a gear connection from the governor to the rack to shift the inner cylinder, substantially as described.

9. A gas-engine, comprising a power-cylinder, two connected pistons therein forming an exhaust-chamber between them, the cylinder having exhaust-ports uncovered by the inner or power piston when in its outermost position, said power-piston having exhaust-ports extending through it, a valve-plate carried by the power-piston and adapted to be held closed by pressure in the cylinder, a spring acting to hold said valve open, a stop engaging said plate to close the exhaust-ports just before ignition, and means for introducing and igniting charges of gas within the engine, substantially as described.

10. An explosion-engine having a cooling-jacket about its cylinder, an air-pump delivering air to the said jacket, and a piston for said pump fixedly connected with the engine-piston, substantially as described.

11. An explosion-engine comprising a power-cylinder, a piston, means for exploding the gas mixture, a pump cylinder and piston for delivering the gaseous mixture to the engine, said pump-cylinder comprising two nested cylinders, the inner cylinder being movable lengthwise within the outer cylinder and having by-pass ports adapted to be uncovered by the pump-piston at the latter end of its compressing stroke, an auxiliary

- head or piston sliding upon the pump-piston rod, and a spring acting upon the same to hold it toward the pump-piston, substantially as described.
- 5 12. A gas-compressing pump for explosion-engines, comprising two concentric cylinders, the inner cylinder being movable lengthwise within the outer one and having by-pass ports adapted to be uncovered by said piston, a piston fitting the inner cylinder, an auxiliary head or piston sliding upon the piston-rod, and a spring acting upon the auxiliary head or piston to hold it toward the pump-piston, substantially as described.
- 15 13. A gas-compressing pump for explosion-engines, comprising two concentric cylinders, the inner cylinder being moved lengthwise within the outer one, and having by-pass ports adapted to be uncovered by its piston, automatic means for moving said inner cylinder, comprising a governor as an actuating member, a piston fitting within the cylinder, an auxiliary head or piston sliding upon the piston-rod, and a spring acting upon the auxiliary head or piston to hold it toward the pump-piston, substantially as described.
- 25 14. A pump for delivering the gaseous mixture to gas-engines, comprising a cylinder having by-pass ports, controlled by its piston, a piston reciprocating therein, means for moving the pump-cylinder relative to the piston-stroke, whereby the time of opening of the by-pass is determined, and a spring-held auxiliary piston slidable upon the pump-piston rod and serving to prevent the escape of the surplus gaseous mixture, substantially as described.
- 30 15. A gas-engine comprising a power-cylinder and piston therein, a pump-cylinder comprising two cylinders one within the other, the inner cylinder having ports or by-passes adapted to connect with opposite sides of the pump-piston, and the outer cylinder being connected with the power-cylinder, a spring-held auxiliary piston slidable on the pump-piston rod and serving to prevent the escape of the surplus gaseous mixture, a rack secured to the inner cylinder, a governor, and a gear connection from the governor to the rack for shifting the inner cylinder, substantially as described.
